UNITED STATES PATENT OFFICE.

AARON ACKER, OF OGDENSBURG, NEW YORK, ASSIGNOR TO THE NEWELL MFG. CO.
INC., OF OGDENSBURG, NEW YORK, A CORPORATION OF MAINE.

DESIGN FOR A CURTAIN-ROD BRACKET.

Application filed May 29, 1922. Serial No. 2,449. Term of patent 14 years.

To all whom it may concern:

Be it known that I, AARON ACKER, a citizen of the United States, residing at Ogdensburg, in the county of St. Lawrence and State of New York, have invented a new, original, and ornamental Design for Curtain-Rod Brackets, of which the following is a specification, reference being had to the

accompanying drawing, forming part thereof.

The figure is a perspective view of a curtain rod bracket showing my new design.

I claim:

The ornamental design for a curtain rod bracket as shown.

AARON ACKER.
